SLIDER FOR FASTENERS

Herman T. Gammons, Natick, Mass., assignor to
 G. E. Prentice Manufacturing Company, New
 Britain, Conn., a corporation of Connecticut

Application June 10, 1933, Serial No. 675,198

31 Claims. (Cl. 24—205)

This invention relates to separable fasteners of the slider actuated type and pertains more particularly to a slider for such fasteners having improved means for supporting the pull tab and for locking the slider in any desired position of adjustment, such locking means being operative to retain the slider in adjusted position whether the slider be moved upwardly or downwardly, respectively, in closing the gap or opening.

10 Sliders provided with so-called double locking devices are in common use in the garment trade, and desirable embodiments of such double locking sliders are disclosed, for example, in the patents to Prentice No. 1,778,338, dated October 14, 15 1930, and No. 1,890,749, dated December 13, 1932.

In all commercial forms of double locking slider with which I am familiar, the pull tab is arranged to swing through an angle of approximately 180° about an axis extending transversely 20 of the slider, and it is necessary to employ a pair of oppositely directed locking devices operative, respectively, at each of the extreme positions of the pull tab, in order properly to hold the slider in adjusted position when the pull tab is arranged at either extremity of its movement. However, but one of such locking elements is useful at any one time, and the presence of the 25 forwardly projecting inactive locking element is, in some constructions, detrimental to the appearance of the slider.

Fasteners of the class to which this invention relates are now applied to a great variety of articles in which a neat and ornamental appearance is a desideratum, and in view of this fact manufacturers of such fasteners have made it a common practice to ornament the pull tab, for example, by embossing, engraving, enameling, or even by in-setting artificial jewels, or otherwise finishing the front exposed face of the tab. 35 Moreover, where ornamentation is not so particularly desired, the prominently exposed face of the pull tab has frequently been employed as a convenient location for a trade name, the maker's name, a patent number, or the like.

40 In the more usual type of slider, unprovided with a lock and always closing the fastener by movement in the same direction, the same face of the pull tab is always exposed to view when the tab is not in use, but when sliders are designed for use in closing a gap either by upward or downward movement, respectively, and in particular when a double locking type of slider is employed, the pull tab is, at different times, disposed in positions substantially 180° apart so that 45 opposite sides of the tab may be alternatively

exposed to view when the tab is not in use. Thus when the tab of such a slider is to be ornamented or is to bear distinctive indicia, it becomes substantially necessary to provide the distinctive ornamental appearance or other characteristic at both faces of the tab, which adds to the cost, and in some cases,—for example, where the tab is ornamented by embossing (which may result in deforming the tab from a flat or plain surface), it is not possible to make both sides 5 10 of the tab alike.

One object of the present invention is to provide a slider capable of use for closing a fastener by upward or downward movement, respectively, so constructed and arranged that the 15 same face of the pull tab may always be exposed at the front when the tab is not in use. A further object is to provide a slider of the double locking type, that is to say, one which may be locked whether the slider be used in closing a 20 fastener by upward or downward movement, respectively, in which a single locking element, if desired, may be employed for locking the slider in adjusted position regardless of whether the pull tab depends toward the neck end of the slider or toward the opposite end. Another object is to provide a double locking construction of 25 simple and efficient type which can be made cheaply, and readily applied to substantially any type of slider body, and which, while durable and reliable in operation, may be made at a relatively 30 low cost.

Other objects and advantages of the invention will be pointed out at greater length in the following description and by reference to the accompanying drawing in which certain desirable 35 embodiments of the invention are shown by way of example.

In the drawing,

Fig. 1 is a fragmentary front elevation illustrating 40 a fastener of well known type having a slider embodying my present invention;

Fig. 2 is a front elevation of the slider of Fig. 1, to larger scale and apart from the fastener units;

Fig. 3 is a fragmentary section substantially on the line 3—3 of Fig. 2, showing in broken lines certain positions of the pull tab;

Fig. 4 is a fragmentary front elevation of the upper end of a pull tab of one preferred construction before assemblage with the slider body;

Fig. 4a is a perspective view, to large scale, of a trunnion device employed in the slider of Fig. 2;

Fig. 5 is a side elevation of the parts shown in Fig. 4;

55

Fig. 6 is a fragmentary longitudinal section through the slider body showing one mode of assembling the pull tab and its locking means with the slider;

5 Fig. 7 is a similar view showing a modified construction;

Figs. 8 and 9 are views similar to Fig. 4, but showing modified forms of pull tab;

10 Fig. 10 is a front elevation similar to Fig. 2, but to smaller scale, showing a modified form of slider and locking means;

Fig. 11 is a side elevation of a pull tab with locking means of modified form;

15 Fig. 12 is a perspective of a trunnion device employed in the construction of Fig. 11;

Fig. 13 is a view generally similar to Fig. 6, but showing the arrangement of Fig. 11 as applied to the slider body;

20 Fig. 14 is a view similar to Fig. 3, but illustrating a slight modification of the locking element;

Fig. 15 is a front elevation similar to Fig. 2, but to smaller scale; illustrating a slider pull with a different form of ornamentation;

25 Fig. 16 is a fragmentary front elevation of a modified construction;

Fig. 17 is a section on line 17—17 of Fig. 16 showing the pull tab in broken lines; and

Fig. 18 is a fragmentary perspective of the pull tab of Fig. 16.

30 Referring to the drawing, the numerals 1 and 2 indicate the usual flexible stringers employed in fasteners of this type for supporting the opposed cooperating series of fastener elements 3 and 4, respectively. These fastener elements may be of any usual construction and are moved into and out of engagement by means of a slider 5, having convergent guide channels for the reception of the respective series of elements. As here shown the slider body is of the general construction disclosed in the patent to Prentice No. 1,900,949, dated March 14, 1933, but it is to be understood that the present invention is applicable to sliders of other specific construction.

35 The slider is actuated by means of a pull tab 6 which, as illustrated in Figs. 1 and 2, is provided with an ornamental front face. Ornamentation produced by embossing, engraving, and in other ways is common in the art.

40 The slider body, as illustrated, comprises the front and rear wings 7 and 8, respectively, united at their upper ends by a neck portion 9 whose lower end, in well known manner, functions as a divider to separate the opposed series of fastener elements as the slider is moved upwardly, and 45 the front wing 7 is furnished with a pair of openings 10 and 11 incidental to the striking up of portions of the metal to form bearing lugs 12 and 13 which, in the completed slider, are fixed, relatively to each other and to the other parts of the slider body. While these lugs may thus be formed as integral portions of the front wing, it is obvious that they may be provided in any other suitable way, for example, by attaching separate elements to the front wing by solder, brazing, or the like, 50 and in that event the openings 10 and 11 need not be formed. The bearing lugs 12 and 13 are provided with aligned openings adapted to receive pintle members 14 and 15, respectively, projecting from the opposite ends of a trunnion 16 (Fig. 4a).

55 70 The pull tab 6, as illustrated in Figs. 4 and 5, for example, preferably is provided with a rearwardly projecting locking element 17 conveniently formed by striking up the metal, thus leaving an opening 18. Obviously this tongue may be made 75 as a separate part and secured to the pull mem-

ber, if desired. The pull tab 6 is also furnished with a pivot or swivel member 19 (preferably integral with the finger-engaging portion of the tab) projecting from its upper end, as viewed in Figs. 1, 2 and 4. The axis of this pivot member extends longitudinally of the tab (that is to say vertically as viewed in Fig. 4) and is substantially within or parallel to the general plane of the pull tab, as illustrated. In assembling the parts, this pivot or swivel member 19 is passed through a diametrical opening 20 in the trunnion member 16, and the extreme end of the pivot member is then headed over to form a retaining head 21 (Fig. 2). The opening 20 is substantially midway between the ends of the trunnion 16 and is disposed perpendicular to the axis of the trunnion, the latter axis extending transversely across the slider body and being located, as indicated in Fig. 2, at a substantial distance from the lower end of the neck 9.

75 In assembling the pull tab with the trunnion 16, 20 and in heading over the pivot or swivel 19, care is taken to permit freedom of rotation of the pull tab 6 with respect to the trunnion 16 about the axis of pivot or swivel member 19,—the pivot member 19 turning in the opening 20.

80 After the pull tab and trunnion have been assembled, the latter is assembled with the slider by introducing the pintle members 14 and 15 into the openings in the tabs 12 and 13, the latter being sprung apart for this purpose or bent up into 30 final position only after the pintle members have been entered in the bearing openings, thus providing in effect, a knuckle or hinge joint between the trunnion and the slider body, the axis of this hinge joint always extending transversely of the 35 slider body. As thus assembled, the swivel connection of the pull tab to the trunnion, and the hinge connection of the latter to the slider body, provides a species of universal joint between the tab and slider body.

85 The front wing 7 of the slider is furnished with a pair of openings 22 and 23 spaced longitudinally of the slider at opposite sides, respectively, of the horizontal plane of the axis of the trunnion member, and at such a distance from such axis that when the pull tab 6 hangs downwardly away from the neck of the slider in the position of Fig. 2, the locking tooth or element 17 may pass through the opening 22 and into locking engagement with the fastener elements 3 and 4, as illustrated in 50 Fig. 3. The locking element 17 may be bent as indicated in Fig. 5 to accommodate it to the position of the openings 22 and 23. The arrangement of parts shown in Fig. 3 is that which they occupy when the slider is to be used in closing a 55 fastener by upward movement, in which event, at the end of the upward movement, the pull tab is allowed to drop and to hang or depend downwardly (or in a direction away from the neck of the slider and toward the lower end of the latter). 60

90 If it should be desired to employ this slider for closing the fastener by downward movement, it is merely necessary to lift the pull tab substantially to a position substantially perpendicular to the slider wing and then to turn it about the 65 axis of its pivot member 19, as illustrated in broken lines at 24 (Fig. 3), through substantially 180°, whereupon the pull tab may be brought to the position shown in broken lines at 25 in Fig. 3, in which the tab depends from its axis toward 70 the neck end of the slider, so that its locking element 17 now passes through the opening 23 for locking engagement with the fastener elements.

95 It is thus possible, by the employment of this 75

arrangement, to use a single locking element for locking the slider, whether the same be employed for closing the gap by upward or downward movement, thus avoiding the provision of a forwardly extending locking member, such as is commonly found in double locking sliders. Moreover, independently of whether the locking element be employed or not, it is possible to keep the same front face of the pull tab always exposed to view, whether the slider be used for closing the gap by upward or downward movement, since, as noted, in swinging the pull tab from the position shown in full lines in Fig. 3 to that shown in broken lines at 25 in the same figure, the pull tab is turned through substantially 180° about its own pivot member 19 while it is being swung through 180° about the axis of the pintle member 16.

This capability of the pull tab to have its same face presented forwardly under all conditions of use is especially desirable where the front face of a tab is ornamented, for example, by surface ornamentation, as shown in Figs. 1 and 2, or, for instance, where the forward face of the pull tab 6^a of the slider 5^a (Fig. 15) is provided with an imitation jewel, ornamental enamel, or any other common form of embellishment. Moreover, since it is common to use the front face of the pull tab as a convenient location for a trademark or patent number, the present invention avoids the necessity of applying the mark to both faces of the pull tab if the slider is to be used for closing the gap in more than one direction.

While a single locking element 17, located substantially on the vertical central plane of the slider, is desirable, it may, under some circumstances, be preferred to provide two rearwardly projecting tooth members or locking elements on the pull tab, adapted to engage the fastener elements at opposite sides of the central axis of the slider. Thus in Fig. 10 the front wing of the slider 5^b is shown as provided with laterally spaced openings 23^a and 23^b, it being understood that a similar pair of openings (corresponding to the opening 22 of Fig. 2) is arranged symmetrically below the axis of the trunnion 16. In this case the pull tab 6^b is furnished with a pair of retaining elements 17^a and 17^b adapted simultaneously to pass rearwardly through one of the pairs of openings in the front wing and to engage the fastener elements of the opposed series at laterally spaced points.

In Fig. 14 a slightly modified construction is illustrated in which the retaining element 17^c of the pull tab is widened at its rear or inner end so that instead of entering substantially between adjacent fastener elements of the series, it presses against the forward faces of such elements so as to avoid distortion or displacement of the elements.

Referring to Figs. 6 and 8, a modified form of pull tab is disclosed, such as tab 6^c, having a pair of laterally directed ears 26 and 27 at its upper end, the tab also being furnished with a rearwardly struck portion 17^c constituting the locking element. In this case the pivot member 19^c is independent of the pull tab proper and is provided with a head at each end, and in assembling the parts the ears 26 and 27 are bent downwardly and inwardly so as to embrace one end portion of the pivot member 19^c, as illustrated in Fig. 6.

In Figs. 7 and 9 a further modified form of pull tab is illustrated, this tab 6^d also having laterally projecting ears 28 and 29. In this case also the pivot member 19^d is separate from the pull

tab and is secured to the latter by bending the ears 28 and 29 so as to embrace a portion of this pivot member, as shown in Fig. 7. In this instance the pivot member is provided with a bent end portion 17^d which constitutes the locking element.

In Figs. 11, 12 and 13 a further modification is illustrated wherein, although the pull tab is arranged to be turned so as always to expose the same face forwardly, a pair of alternatively acting locking elements is employed instead of the single locking element of the previous constructions. In this arrangement, as illustrated in Fig. 12, the trunnion member 16^e is provided with the pintle members 14 and 15 and with the transverse bearing opening 20 in the same way as the trunnion 16 above described. The pull tab 6^e is provided with a pivot member 19 in the same way as that of Fig. 4, and this pivot member is disposed in the opening 20 of the trunnion member and headed over at its end in the same way as that of the tab 6. The trunnion member 16^e is provided with a pair of locking elements 30 and 31 projecting, respectively, in opposite directions and at substantially right angles to the axis of the opening 20. The front wall of the slider in this instance is furnished with but a single opening 32 (Fig. 13) disposed immediately behind the trunnion 16^e, and the locking elements 30 and 31 alternatively projected through this opening and into engagement with the fastener elements, in accordance with the position of the pull tab. The pull tab may be swung about the axis of the trunnion 16^e so as to depend, when released, either from the neck end or the opposite end of the slider, in accordance with whether the slider is used for closing a gap by downward or upward movement, respectively, and in either event, adequate locking action is obtained by the construction disclosed. By reason of the mounting of the pull tab 6^e, so as to turn relatively to the trunnion 16^e, it is possible to keep the same face of the pull tab exposed to the front in either of its locking positions in the same way as described with reference to the preceding constructions.

In the construction illustrated in Figs. 16, 17 and 18, the pull tab 6^m has a ball or substantially spherical knob 33 at its upper end. Preferably this ball or knob terminates in a substantially rectangular stem 34. If a locking element be desired, this may be provided, for example, by striking out a portion of the metal from the pull tab so as to provide a rearwardly projecting pin or cam element 35 as in the arrangement of Fig. 5, for example. The pull tab illustrated in Figs. 16, 17 and 18 may thus be made from a single piece of metal by appropriate manipulation.

The pull-supporting lugs or ears 12^a, 13^a are formed, for example, as described with reference to Fig. 2, but in this case they are furnished with spherically curved bearing socket cavities 35^a in their adjacent vertical faces, such cavities being conveniently formed by embossing, stamping or other appropriate method. These ears 65 are so relatively disposed in the completed slider that the ball 33 of the pull tab is confined between them,—being free to turn in the bearings provided by the opposed cavities in the faces of the lugs. Preferably, the lugs 12^a, 13^a are so close 70 together as to form guides for the lateral faces of the rectangular stem 34 of the pull tab, thus normally preventing the finger-engaging portion of the pull tab 6^m from being turned about an axis lying in the vertical front-to-rear central 75

plane of the slider body. However, these lugs are furnished with channels 38 leading forwardly from their respective bearing cavities, and these channels afford clearance for the stem 34 of the 5 tab, after the latter has been swung forwardly to a position substantially at right angles to the plane of the front wing. In this position, the tab may be turned about a front-to-rear axis in its own plane through substantially 180°, and 10 then may be swung down again into a position substantially parallel to the front wing but so as to extend toward the opposite end of the slider from that toward which it first extended. This arrangement is advantageous since the pull 15 tab with its pivot means and locking element may be made as a single integral part.

While I have herein illustrated certain desirable embodiments of the invention by way of example, it is to be understood that changes in 20 size, proportion and relative arrangement of parts, as well as the substitution of materials and equivalents, may all be made without departing from the spirit of the invention as defined in the appended claims.

25 While I have herein made reference to the upper and lower ends of the slider, and to upward or downward movement of the pull tab, it is to be understood that all such reference to direction are for convenience in description, and 30 with reference to the illustrations, and are not to be regarded as in any sense limiting the claims to particular positions of the slider when in use.

Likewise when I make reference to the "plane" 35 of the pull tab, I do not thereby intend to indicate that the tab is mathematically flat, but merely to facilitate the description of the relation of parts, and to refer to a general and usual formation of the tab in which the finger-engaging portion is transversely broad.

40 I claim:

1. A slider for use in slide operated fasteners, 45 said slider having parts defining convergent guide channels for opposed series of fastener elements, and a pull tab for actuating the slider, pull tab supporting means carried by the slider, said supporting means providing an axis extending longitudinally of the pull tab and substantially in the plane of the latter and about which the tab may be rotated through at least 180°, said 50 supporting means also providing a fixed axis extending transversely of the slider and about which the pull tab may be swung upwardly or downwardly through substantially 180°.

2. A slider for fasteners of the class described, 55 said slider having a body comprising front and rear wings and a divider member, a pull tab for moving the slider, and pivot means, carried by the slider body, at a point intermediate the divider member and the lower end of the slider 60 body, said pivot means supporting the pull tab and comprising parts defining two axes substantially perpendicular to each other about which the pull tab may turn thereby to permit the pull tab to swing upwardly or downwardly between 65 positions substantially 180° apart and in each of said positions to expose the same face of the pull tab forwardly.

3. A slider for fasteners of the class described, 70 said slider having a part comprising front and rear wings united by a neck, a pull tab for moving the slider, and tab supporting pivot means carried by the slider, said pivot means comprising parts defining two axes substantially at right angles to each other about each of which the tab 75 may be swung through substantially 180°, one of

said axes always being transverse of the slider body and substantially parallel to the front wing, the parts which define said latter axis being fixed relatively to the slider body.

4. A slider for use in slide operated fasteners 5 comprising interengaging series of fastener elements, said slider having parts defining convergent guide channels for the opposed series of fastener elements, and a pull tab for actuating the slider, the pull tab having a distinctive front 10 face, fastener-engaging locking means carried by the pull tab, the slider having spaced passages through which the locking means may project to operatively engage the fastener elements when the tab occupies either of two predetermined positions, respectively, and connections uniting the pull tab to the slider, said connections comprising parts which define a predetermined axis, fixed with respect to the slider, about which the tab may be swung either upwardly or downwardly 20 into one of said two predetermined positions and in each of which it is substantially parallel to the front face of the slider, said connections also comprising parts which define an axis extending longitudinally of the pull tab and which is al- 25 ways substantially in the plane of the tab and about which the tab may swivel.

5. A slider for use in slide operated fasteners, 30 said slider having parts defining convergent guide channels for opposed series of fastener elements, a pull tab for actuating the slider, and connections uniting the pull tab to the slider, said connections comprising parts certain of which define a swivel axis substantially in the plane of the pull tab and extending longitudinally of the tab, 35 and certain of the parts being fixed to the slider and defining a fixed hinge axis extending transversely of the slider and from which the tab normally depends when in use.

6. A slider for use in slide operated fasteners, 40 said slider having parts defining convergent guide channels for opposed series of fastener elements and a pull tab for actuating the slider, a trunnion member mounted to turn about an axis extending transversely of and substantially parallel to 45 the front face of the slider, fixed bearing means for said trunnion member, said bearing means being carried by the slider, a pull tab supported by the trunnion member and normally depending from the latter when not in use, and means 50 uniting the pull tab to the trunnion member so constructed and arranged as to permit the pull tab to turn about an axis substantially perpendicular to that of the trunnion member.

7. A slider for use in slide operated fasteners, 55 said slider having a body comprising front and rear wings and a neck and defining convergent guide channels for opposed series of fastener elements, a pull tab, and universal joint connections between the pull tab and the slider, said 60 connections comprising lugs fixed to the slider body and defining a hinge axis extending transversely of the slider body about which the tab may swing into either of two positions substantially parallel to the front of the slider and 180° 65 apart, the universal joint connections also comprising parts defining a swivel axis substantially in the plane of the pull tab and extending longitudinally of the latter whereby the tab may be turned to expose the same face when the tab 70 occupies either of the aforesaid positions.

8. A slider for use in slide operated fasteners, 75 said slider having parts defining convergent guide channels for opposed series of fastener elements, and a pull tab for actuating the slider, pull tab 80

supporting means carried by the slider, said supporting means providing a fixed axis transverse of the slider about which the pull tab may swing upwardly or downwardly through substantially 180°, said supporting means also providing a second axis substantially perpendicular to the first about which the tab may be turned through at least 180°.

9. A slider for use in slide operated fasteners, said slider having parts, including a front and rear wing, defining convergent guide channels for opposed series of fastener elements, a pull tab for actuating the slider, and tab supporting means carried by the slider, said supporting means including spaced bearings defining an axis extending transversely of the slider, a part turning in said bearings, and a connecting element secured to said part so as to turn about an axis perpendicular to said first axis, the pull tab being so secured to said connecting element that said latter axis lies substantially in the plane of the pull tab.

10. A slider for fasteners of the class described in which opposed series of fastener elements are moved into and out of engaging relation by movement of the slider, said slider having a body comprising front and rear wings, a pull tab for moving the slider, and a single locking member carried by the pull tab, said locking member being operative, by engagement with fastener elements of the series, to lock the slider in adjusted position, the front wing of the slider having spaced openings through either of which alternatively the locking member may be projected thereby operatively to engage fastener elements of the series when the tab occupies either of two predetermined positions, and pivot means uniting the pull tab to the slider body, said pivot means providing a universal connection defining axes about which the pull tab may be moved to place it in either of said predetermined positions.

11. A slider for use in slide operated fasteners said slider having parts defining convergent guide channels for opposed series of fastener elements, and a pull tab for actuating the slider, connections uniting the pull tab to the slider, said connections comprising means fixed to the slider and defining a fixed axis which extends transversely of the slider and which is substantially parallel to the front face of the latter and about which the pull tab may swing upwardly or downwardly through substantially 180° into either of two positions in which it is substantially parallel to the front face of the slider, and slider locking means projecting from one face of the pull tab, said connections including swivel means such that the tab may be turned to cause the locking means to project toward the slider body when the tab occupies either of said positions.

12. A slider for use in slide operated fasteners, said slider having parts defining convergent guide channels for opposed series of fastener elements, and a pull tab for actuating the slider, slider locking means projecting from one face of the pull tab, and connections uniting the tab to the slider, said connections comprising parts defining a predetermined axis fixed relatively to the slider about which the tab may be swung upwardly or downwardly, said connections also comprising parts defining an axis, always substantially in the plane of the tab, about which the tab may swivel.

13. A slider for fasteners of the class described, said slider having a body comprising front and

rear wings united by a neck, a pull tab for moving the slider, a pair of spaced ears projecting forwardly from the front wing, the opposed faces of said ears having spherically curved bearing sockets, and a ball member carried by the pull tab, said ball being disposed between said ears and turning freely in the opposed sockets, thereby permitting the tab to be swung upwardly or downwardly between positions substantially 180° apart, and a single locking element carried by the pull tab and projecting from one face of the latter, said locking element being operative to lock the slider when the tab occupies either of said two positions.

14. A slider for fasteners of the class described in which opposed series of fastener elements are moved into and out of engaging relation by movement of the slider, the slider having a body comprising front and rear wings united by a neck, a pull tab, connections uniting the pull tab to the slider body, said connections comprising means fixed to the slider body defining a fixed pivotal axis extending transversely of the slider body and spaced from the neck of the latter, the pull tab being arranged to swing about said axis between either of two positions substantially 180° apart, and locking means on the pull tab at a substantial distance from said axis, the slider having apertures above and below said axis through either of which, alternatively, according to which of said positions the pull tab occupies, the locking means may project to engage the fastener elements.

15. A slider for fasteners of the class described in which opposed series of fastener elements are moved into and out of engaging relation by movement of the slider, said slider having a body comprising front and rear wings united by a neck, a pull tab, a locking element projecting from one face only of the pull tab, and connections uniting the tab to the slider body, said connections comprising parts constituting a universal joint including bearing means fixed to the slider defining an axis about which the tab may be swung so as to occupy either of two positions in which it is substantially parallel to the front wing, said universal joint parts also providing an axis substantially perpendicular to said first axis about which the tab may swivel so that when in either of said positions the locking element may be caused to project rearwardly toward the front wing of the slider into operative engagement with some of the fastener elements.

16. A slider for use in slide operated fasteners, said slider having a body comprising front and rear wings and a neck and defining convergent guide channels for opposed series of fastener elements, a pull tab, connections uniting the pull tab to the slider body, said connections comprising parts defining a hinge joint and a swivel joint about either of which the tab may turn, the axis of the hinge joint extending transversely of the slider and being substantially parallel to the front wing of the slider and the axis of the swivel joint being substantially perpendicular to the hinge axis, the hinge joint comprising bearing means fixed to the slider body, the pull tab having locking means projecting from one face only thereof.

17. A slider for use in slide operated fasteners, said slider having a body comprising front and rear wings and a neck and defining convergent guide channels for opposed series of fastener elements, a pull tab having locking means at its rear side only, said locking means being operative

by engagement with fastener elements of the series to retain the slider in position, connections uniting the pull tab to the slider body, said connections including means fixed to the slider body and defining a fixed axis extending transversely of the slider about which the pull tab may swing upwardly or downwardly into either of two positions in which it is substantially parallel to the front of the slider, said connections also comprising swivel means defining an axis substantially in the plane of the pull tab about which the latter may turn.

18. A slider for fasteners of the class described, said slider having a body comprising front and rear wings united by a neck, a pull tab, connections uniting the pull tab to the slider body, said connections including means fixed to the slider body and defining a fixed axis spaced from the neck of the slider and extending transversely of the slider body about which the tab may be swung from a position substantially parallel to the front wing to another position substantially parallel to the front wing and 180° removed from the first position, and a locking prong projecting from one face only of the pull tab and operative to enter between fastener elements of the series and thereby to lock the slider, said connections comprising swivel means defining an axis substantially in the plane of the tab about which the latter may turn.

19. A slider for fasteners of the class described, said slider having a body comprising front and rear wings united by a neck, a pull tab, connections uniting the pull tab to the slider body, said connections including means fixed to the slider body and defining a fixed axis which extends transversely of the slider body and about which the tab may be swung into either of two different positions in each of which it is substantially parallel to the front wing, and a locking cam projecting from one face only of the tab, said cam being operative by frictional engagement with the fastener elements, to lock the slider in adjusted position, said connections comprising swivel means defining an axis substantially in the plane of the pull tab about which the latter may turn.

20. A slider for fasteners of the class described, said slider having a body comprising front and rear wings united by a neck, a pull tab for moving the slider, means carried by the slider body defining a pivotal axis about which the pull tab may swing upwardly or downwardly, the front wing of the slider body having openings therethrough disposed above and below the horizontal plane of the pivotal axis of the tab, and a locking element disposed at one face of the tab and operative alternatively to project through one or the other of said openings into locking contact with the fastener elements in accordance with the selected position of the pull tab.

21. A slider for fasteners of the class described, said slider having a body comprising front and rear wings united by a neck, a pull tab, supporting means carried by the slider body defining an axis transverse of said body about which the tab may be swung upwardly or downwardly into positions substantially parallel to the front wing, said front wing having a pair of openings spaced apart longitudinally of the slider, and cam means projecting from one face of the tab and operative in accordance with the selected position of the tab to project through one or the other of said openings into locking contact with the fastener elements.

22. A slider for fasteners of the class described,

said slider having a body comprising front and rear wings united by a neck, the front wing having a pair of openings spaced apart longitudinally of the slider, a pull tab, a locking element carried by the pull tab, and pivot means carried by the slider body so supporting the pull tab as to permit said locking element to be projected through either of said openings at will.

23. A slider for fasteners of the class described, said slider having a part comprising front and rear wings united by a neck, and locking means operative to retain the slider in adjusted position, said locking means comprising a pull tab having a locking element projecting rearwardly therefrom, and connections uniting the pull tab to the slider body, said connections comprising bearing means fixed to the slider body and defining an axis extending transversely of the slider body about which the tab may be swung, so as to lie substantially parallel to the front wing of the slider in either of two different positions, said connections comprising parts defining a swivel joint having an axis substantially perpendicular to said transverse axis about which the tab may be turned so that the same surface of the tab may be directed forwardly regardless of which of said positions the tab may occupy.

24. A slider for use in slide operated fasteners, said slider having a body comprising front and rear wings and a neck and defining convergent guide channels for opposed series of fastener elements, a pull tab, and tab supporting means carried by the slider comprising a trunnion member arranged to turn about a fixed axis extending transversely of and substantially parallel to the front face of the slider, and a swivel pin uniting the pull tab to the trunnion so that the pull tab may turn about an axis substantially perpendicular to that of the trunnion, and a locking element carried by the pull tab.

25. A slider for use in slide operated fasteners, said slider having a body comprising front and rear wings and a neck and defining convergent guide channels for opposed series of fastener elements, the front wing of the slider having a pair of openings spaced longitudinally of the slider, a pivoted pull tab on the slider, tab supporting means mounted on the slider, and a single locking element carried by the pull tab, the tab supporting means being so constructed and arranged that the locking element may be projected through either of said openings into engagement with the fastener elements.

26. A slider for use in slide operated fasteners, said slider having a body comprising front and rear wings and a neck and defining convergent guide channels for opposed series of fastener elements, a pull tab, a single locking element carried by the pull tab, connections uniting the pull tab to the slider body, said connections comprising bearing means fixed to the slider body and parts movable relatively to said bearing means, the connections defining axes substantially at right angles to each other about either of which the pull tab may turn, one of said axes extending transversely of the slider body and being substantially parallel to the front wing, and the other axis being substantially in the plane of the pull tab, whereby the single locking element may be caused to engage fastener elements of the series when the tab occupies either of a plurality of predetermined positions.

27. A slider for use in slide operated fasteners, said slider having a body comprising front and rear wings and a neck and defining convergent

- guide channels for opposed series of fastener elements, the front wing of the slider having a pair of openings spaced longitudinally thereof, tab supporting means defining an axis intermediate said openings and about which the tab swings, and a locking element carried by the tab, said supporting means being constructed and arranged to permit said locking element to enter either of said openings at will.
- 10 28. A slider for use in slide operated fasteners, said slider having parts defining convergent guide channels for opposed series of fastener elements and a pull tab for actuating the slider, a trunnion member mounted to turn about an axis extending transversely of and substantially parallel to the front face of the slider, bearing means for said trunnion member, said bearing means being carried by the slider, a pull tab, swivel means uniting the pull tab to the trunnion member and permitting the pull tab to be turned about an axis substantially perpendicular to that of the trunnion member, and a locking element carried by the trunnion member and operative to lock the slider in adjusted position.
- 15 29. A slider for use in slide operated fasteners, said slider having parts defining convergent guide channels for opposed series of fastener elements and a pull tab for actuating the slider, a trunnion member mounted to turn about an axis extending transversely of and substantially parallel to the front face of the slider, bearing means for said trunnion member, said bearing means being carried by the slider, a pull tab, swivel means uniting the pull tab to the trunnion member and permitting the pull tab to be turned about an axis sub-

stantially perpendicular to that of the trunnion member, and a pair of locking elements carried by the trunnion member, said elements being operative, respectively, to lock the slider in adjusted position when the trunnion occupies either of two different positions substantially 180° apart.

30. A slider for use in a slide operated fastener, said slider having parts defining convergent guide channels for opposed series of fastener elements, a pull tab for actuating the slider, and connections uniting the pull tab to the slider, said connections comprising parts fixed to the slider and which define a knuckle joint whose axis extends transversely of the slider, the connections comprising parts defining a swivel axis extending substantially perpendicular to the knuckle joint axis about which the tab may turn.

31. A slider for use in slide operated fasteners comprising interengaging series of fastener elements, said slider having a body comprising spaced front and rear wings, a slider-actuating pull member always disposed at the front of the slider body, a locking part carried by the pull member, the front wing being of such shape as to expose the fastener elements of the series at two predetermined spaced points, and connections movably uniting the pull member to the slider body, said connections comprising relatively movable parts designed and arranged to allow the pull member to be shifted from a position in which the locking part engages the fastener elements at one of said points of exposure to a position in which the locking part engages the fastener elements at the other of said points of exposure.
